FACSIMILE TRANSMITTER

La Verne R. Philpott, Wilkinsburg, Pa., assignor
to Westinghouse Electric & Manufacturing
Company, a corporation of Pennsylvania

Application May 28, 1930. Serial No. 456,332

6 Claims. (Cl. 178—5)

My invention relates to the transmission of pictures, images, printed matter or the like wherein a beam of light is caused to traverse successive elements of a subject, the resultant light variations being subsequently translated into corresponding electric currents for transmitting over wire or through the ether. More particularly, my invention relates to improvements in such transmitting systems whereby either secret 10 or selective transmission may be possible.

It is conceivable that under certain conditions, it might be desirable to transmit only definite portions or selected outlines appearing on a picture or facsimile to be sent to some distant receiver. In transmitting code messages, for example, it would constitute a great convenience to the writer of the message to have the code key visibly printed on the message paper, thereby eliminating the necessity of having a code book 20 available at all times for reference and use. It would not be desirable, however, to transmit the code key along with the message and, by my invention, I have made it possible to transmit the one without the other.

25 This particular system of code communication would be admirably adapted to present day business methods and conditions.

Additional practical applications of my invention readily suggest themselves. Drawings or 30 sketches may be transmitted from coordinated paper without the necessity of transmitting the rulings on said paper, the drawings or sketches being received on a clear white background, whereupon they become much more legible and discernible.

Where it becomes desirable to transmit, in secrecy, the location of enemy positions or the like, such locations may be indicated on a blank or dummy map and then transmitted. The reproduction obtained at the receiving end will 40 merely disclose a number of check marks or other symbols on a blank background from which no information can be obtained. This may then be so superimposed upon a blank or dummy map, similar to the one utilized in transmission, as to 45 make understandable the information conveyed by the symbols.

It will be apparent, therefore, that my invention 50 will open up a wide field of use for facsimile-reproduction systems, as it lends itself to numerous novel and highly desirable applications.

It is accordingly one object of my invention to provide a method of facsimile transmission whereby it becomes possible to transmit only desired 55 portions of a facsimile.

Another object of my invention is to provide a facsimile transmitter capable of selective or secret transmission.

Another object of my invention is to provide a 60 facsimile transmitter which is color sensitive, whereby certain desirable results may be accomplished.

Another object of my invention resides in a 65 novel photo-cell arrangement for a facsimile transmitter.

Another object of my invention is to accomplish 70 the above objects in a very simple and inexpensive manner.

Additional objects of my invention will be disclosed in the following description of my invention, taken in conjunction with the accompanying 75 drawing wherein the single figure represents a plan view of apparatus embodying my invention, as adapted to a transmitter of a commercial type.

Referring more particularly to the drawing, the apparatus disclosed comprises a source 1 of light energy enclosed by a protective tube 3, which, in addition to its protective function, is utilized as 80 a light mask. A narrow slit 5 in the tube 3 provides for the production or creation of a beam of energy externally of said tube, said beam to be utilized for scanning purposes.

Associated with the light source 1 and mask 3, I provide a chopper mechanism, the general purpose of which is to interrupt the beam of energy at a predetermined rate, preferably at a frequency lying within the audio-frequency range. The beam, so interrupted, is subsequently transformed 85 into an electric current of the same frequency, which is modulated by variations in picture intensities, as will be more fully emphasized in describing the apparatus for producing the desired results.

The chopper comprises a member 7 of inverted cup or cam shape rotatably mounted in concentric relationship to said tube 3 and provided with a plurality of slits 9 in spaced relationship about its cylindrical surface, the surface portions between said slits being individually of sufficient width to substantially cover the slit 5 and thus cut off the beam of energy at definite intervals for a very small fraction of a second. The chopper structure just described constitutes 95 a novel improvement in choppers and constitutes the subject matter of Patent No. 1,877,566, granted Sept. 13, 1932, in which I am a joint applicant.

A support or holder for mounting a view 11 or facsimile to be transmitted comprises a cylinder 13 about which said view is adapted to be wrapped and to which it is temporarily secured. 100 105 110

The cylinder, when in action is caused to rotate and, at the same time, assume a translatory motion, whereby the beam of energy, when directed against, and focused upon, the view will, in the course of a short interval of time, depending upon speed of operation of the apparatus, scan the entire view.

The beam, as reflected from the picture, will be varied in intensity in accordance with particular make up of the view or picture to be transmitted, these variations resulting in a modulation of the audio-frequency current produced by the chopper structure.

The transformation of the modulated beam into corresponding electric currents is made possible by the use of photo-sensitive devices 15 connected in an electric circuit and so positioned as to receive a large proportion of the reflected energy. Various means have been resorted to for obtaining a sufficient portion of the reflected energy to operate the cells in a practical and efficient manner. Cells of special construction have been used, and reflectors of various types have been tried for concentrating the reflected energy upon the cathode of a photo-cell. Specially constructed tubes are expensive, and artificial energy reflectors are inefficient. I have obtained excellent results with the use of two-photo-cells of standard construction, one on each side of the beam of energy and rather close to the picture. A sufficient portion of the reflected energy will strike the cells to produce the desired results. The use of a pair of standard cells, as disclosed, comprises, in so far as I am aware, a novel improvement in facsimile-transmitting apparatus and reduces both the initial cost and the upkeep of such apparatus.

The apparatus so far described is capable of transmitting facsimiles in the normal manner. In order to render such apparatus capable of secret or selective transmission, I removably position, in the path of the beam of energy, a filter 17 capable of intercepting undesirable components of said beam and passing only certain desirable components. In my preferred embodiment, the filter which I utilize comprises a small piece of red glass or other translucent material, capable of intercepting all the undesirable color components from the beam except, of course, the red component, to which component, the normal standard photo-cells are quite sensitive. The red component, in striking the view or picture to be transmitted, will be reflected with substantially equal intensity from a picture element having a red background as from one having a white background; and it is to this phenomenon that I may attribute the operativeness of my invention. The modulation of the current in the photo-cell circuits will be substantially the same for the red portions of the picture as for the white and, so far as the receiving apparatus is concerned, the red portions of the picture being transmitted do not exist. The received picture, accordingly, will show white where the transmitted picture shows red. It may be stated, therefore, that the one color merges into that of another.

Referring back to the practical adaptations of my invention, the above description readily suggests the manner in which the desired results may be obtained. Those elements of the picture or subject which it is desired shall not be transmitted should be printed or written in red, and, with a filter in the path of the beam which is capable of intercepting all undesirable components thereof, thus permitting only the red com-

ponent to pass, the desired results will be obtained.

While I have disclosed, as my preferred embodiment, the use of a red filter, other color filters might be used in lieu thereof, or any desired combination of color filters may be resorted to, in which cases, with the use of suitable photo-sensitive devices, picture elements corresponding to the filtered beam will merge with the background of the view or picture, as received.

Also, I consider it to be within the scope of my invention to provide, in place of a single filtering means, a color wheel comprising a plurality of filtering means disposed about its circumference, whereby any desired filter may be easily accessible.

In lieu of independent filtering means, as described above, it is also within the province of my invention to utilize a source of energy having inherently the desired characteristics, such as various colored flames, or I might make use of various colored light bulbs or other similar contrivances.

While the above description of my invention has related more or less to the use of light rays as a scanning medium, I consider my method and the broad principles of my invention as covering the use of a beam of energy in general, whether it be a ray of the visible spectrum or an infra-red or ultra-violet ray etc. there being no sharp physical distinction existing between them.

In view of the conditions stated above and the fact that various additional modifications of the instrumentalities described which might be suggested which would be within the scope of my invention, I do not desire to be limited to the specific details set forth except in so far as may be required by the prior art and by the appended claims.

I claim as my invention:

1. The method of selectively transmitting views comprising preparing a subject having portions thereof which it is not desired to transmit, of colors distinct from other colors which it is desired to transmit, said other colors comprising a view in themselves, producing a beam of energy having the characteristics of being reflected with substantially equal intensity from said distinctive colors and causing said beam to scan said subject and thereafter reproducing said view into the form of a record in which the undesirable colors are merged into a common color.

2. In view-transmitting apparatus, means for producing a beam of energy, means for causing said beam to scan a view to be transmitted whereby said beam will be modulated, said view having guiding indications thereon which are distinct in color from the rest of the view, and means for transforming said modulated beam into a corresponding electric current, said means comprising a pair of standard photo-sensitive devices situated adjacent to said beam and to said view said photo-sensitive devices being substantially equally sensitive to both the background of said view and the color of said guiding indications whereby said guiding indications will become merged with the background of said view as reproduced.

3. In a system of the facsimile type wherein a beam of energy scans a view to be transmitted and wherein the beam as modulated by the view is directed upon photo-sensitive means, the method of reproducing desired portions only of a view, said method comprising preparing a view having

portions thereof which it is not desired to transmit, of a color distinct from the color of other portions which it is desired to transmit, scanning a continuous area of said view, modifying the beam to affect the photo-sensitive device in the same manner when directed toward the undesired portions of the view as when the beam is directed toward the background of said view, and reproducing said view into the form of a record in which the undesirable portions are merged with the background.

4. In a system of the facsimile type wherein a beam of energy scans a view to be transmitted and wherein the beam as modulated by the view is caused, in turn, to modulate an electric current, the method of transmitting selected portions of a view, said method comprising giving to the undesired portions of the view a color characteristic differing from that of the desired portions, modifying said beam when directed toward the undesired portions of the view, to modulate an electric current in the same manner when directed toward the undesired portions of the view, as said view and reproducing said view into the form of a record in which the undesirable portions are merged with the background.

5. In a system of the facsimile type wherein a beam of energy scans a view to be transmitted and wherein the beam as modulated by the view is, in turn, caused to modulate an electric current, the method of transmitting comprising placing a view on paper having indicating means thereon of different color characteristics than said view for facilitating the placing of said view, said indicating means being undesired in the reproduced view, modifying the scanning beam to effect the current in the same manner when directed toward the undesired portions, as when said beam is directed toward the background of the view and reproducing said view into the form of a record in which the undesirable portions are merged with the background.

6. The method of secret signalling with apparatus of the facsimile type, comprising placing information on paper with the aid of indications on said paper, electrically transmitting to a receiving station said information to the exclusion of said indications and reproducing said information on paper having similar indications thereon whereby said information may be interpreted.
